Atty's:

UNITED STATES PATENT OFFICE

JOHN F. SKOLD, OF CHICAGO, ILLINOIS

DESIGN FOR A RADIATOR

Application filed April 21, 1930. Serial No. 35,336. Term of patent 3½ years.

To all whom it may concern:

Be it known that I, JOHN F. SKOLD, a citizen of the United States, residing at Chicago, in the county of Cook and State of Illinois, having invented a new, original, and ornamental Design for Radiator, of which the following is a specification, reference being had to the accompanying drawing, forming part thereof.

The figure is a perspective view of a radiator showing my new design.

The side and the end of the radiator which are opposite to the side and end of the radiator shown in the drawing are the same as the latter in appearance.

I claim:

The ornamental design for a radiator as shown.

JOHN F. SKOLD.
